Primary Examiner—Susan J. Lucas*Assistant Examiner*—Pamela Burgess*Attorney, Agent, or Firm*—Terry M. Gerstein**[57] CLAIM**

The ornamental design for a unit for teaching dancing, as shown and described.

DESCRIPTION

FIG. 1 is a front, top and side perspective view of the unit for teaching dancing showing my new design, with the remote control and the recorded information player being part of the unit and being shown in full lines to indicate that they are included with the unit;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof;

FIG. 7 is a front elevational view thereof; and,

FIG. 8 is a reduced scale top perspective view thereof.

The broken lines shown in FIGS. 1, 2 and 8 are for illustrative purposes only and form no part of the claimed design.

1 Claim, 5 Drawing SheetsFIG. 7.

FIG. 6.
